US00D591184S

(12) **United States Design Patent**
Gretton

(10) **Patent No.:** **US D591,184 S**
(45) **Date of Patent:** **** Apr. 28, 2009**

(54) **NAVIGATION SYSTEM WITH SUCTION PAD**

(75) Inventor: **Mark Gretton**, London (GB)

(73) Assignee: **Tom Tom International B.V.**,
Amsterdam (NL)

(**) Term: **14 Years**

(21) Appl. No.: **29/312,914**

(22) Filed: **Nov. 22, 2008**

Related U.S. Application Data

(62) Division of application No. 29/296,283, filed on Oct. 17, 2007, now Pat. No. Des. 581,818.

(51) **LOC (9) Cl.** **10-04**

(52) **U.S. Cl.** **D10/65**
